DESIGN FOR A DRESS ENSEMBLE

Samuel Zahn, New York, N. Y.

Application December 4, 1937, Serial No. 73,345

Term of patent 3½ years

To all whom it may concern:

Be it known that I, Samuel Zahn, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

Figure 1 is a front view of a dress ensemble showing my new design.

Figure 2 is a rear view of the dress ensemble shown in Figure 1.

The sleeves of the dress section are identical in appearance to the sleeves on the jacket. The front and rear body portions of the dress are plain with the exception of the front tucking, as shown.

The characteristic feature of my design resides in the combination on the ensemble disclosed of the specific crushed applique on the jacket and belt sections, as shown.

I claim:

The ornamental design for a dress ensemble, substantially as shown, and described.

SAMUEL ZAHN.
